UNITED STATES PATENT OFFICE.

FRANK W. HEWITT, OF ARLINGTON, MASSACHUSETTS, ASSIGNOR TO SIMPLEX ELECTRIC HEATING COMPANY, OF BOSTON, MASSACHUSETTS, A CORPORATION OF MASSACHUSETTS.
ELECTRIC RANGE.

1,307,048.

Specification of Letters Patent. Patented June 17, 1919.

Application filed December 30, 1918. Serial No. 268,783.

To all whom it may concern:

Be it known that I, FRANK W. HEWITT, a citizen of the United States, residing at Arlington, county of Middlesex, State of Massachusetts, have invented an Improvement in Electric Ranges, of which the following description, in connection with the accompanying drawing, is a specification, like characters on the drawing representing like parts.

This invention relates to the construction of an electric range in which cooking plates are associated with a baking oven and usually with other heating compartments.

15 The main object of the invention is to provide a construction in which the various switches controlling the various heating units, the various fuses and terminals or other electric distributing fittings may all be assembled in a distributing box which may be put in place after assembling and to which access may be readily had when in place.

20 The object of the invention is further to provide a distributing box so positioned and located that the circuit wires leading to the heating units of the oven or other heating compartment may pass directly through the side wall thereof and the circuit wires leading to the cooking plates may pass directly 25 from the distributing box to the cooking plates.

25 The invention also has for its object to provide a distributing box located directly against the side wall of the oven and provided with an opposite side closure opening over the cooking plates so that ready access 30 may be had to the interior of the distributing box upon the opening or removing of the closure.

35 The invention also has for its object to provide for the location of all the controlling switches centrally of the range in a vertical row.

40 These and other objects and features of the invention will appear more fully from the accompanying description and drawings and will be particularly pointed out in the claims.

In the drawings,

45 Figure 1 is a view in perspective of one form of range embodying the invention;

Fig. 2 is a detail partially in vertical cross section through the side wall of the distrib-

uting box and the side wall of the oven showing the binding posts and supporting bracket for connection with the wires leading to an oven heating unit;

55 Fig. 3 is a side elevation of the distributing box with a portion of the construction broken away, with the main circuit and various switches, fuses and terminals shown in position but with the wiring from the switches omitted;

60 Fig. 4 is a view in cross section of the distributing box;

65 Fig. 5 is a diagrammatic plan of the wiring in and leading from the distributing box.

An electric range embodying this invention 70 comprises essentially a horizontal table 6 and a vertical oven. In the table are mounted a plurality, here shown as four in number, of cooking plates 7 each containing one or more electric heating units. This table may be and preferably is supported by 75 legs 8 from the floor and beneath the table a shelf 9 may be provided.

The oven 10 extends vertically with respect to the table 6 and may be and preferably is mounted on top of the table and is 80 provided with one or more, in the form illustrated with two, heating units. As many ovens or heating compartments may be arranged in vertical series as desired. As illustrating this feature a broiling oven 11 85 is shown above the main or baking oven 10 and provided with a single heating unit.

90 In this invention a distributing box is provided upon which are mounted the various switches, fuses, terminals and other fittings requisite for distributing the electric current from the main line to the various heating units. This distributing box is located at the side of the vertically arranged oven or tier of heating compartments and at 95 that side facing the cooking plates. This arrangement enables the circuit wires to lead directly from the distributing box through the side wall of the ovens or heating compartments into the interior thereof. Thus 100 these heating units may readily be disconnected and connected for repair or replacement and thus also the wiring in the oven is reduced to the minimum. This arrangement also enables the circuit wires to lead 105 directly from the distributing box through

the end, if the oven is located above the table through the lower end, to the cooking plates, thus simplifying the wiring to the minimum. This arrangement also enables 5 the main circuit wires to be brought directly into the distributing box from the back of the range through the rear end of the distributing box and it also enables if desired the main line switch to be located in the dis- 10 tributing box.

It will thus be seen that a very compact and simple structure is provided in which the wiring in the range is reduced to the minimum and in which direct connections 15 are made from the distributing box to all the heating units.

The distributing box is a narrow vertical structure being only of sufficient width to accommodate the necessary electrical fittings.

20 This enables the switches for all the heating units to be arranged in a single vertical row centrally of the range where ready access thereto may be had.

The distributing box being located at the 25 side of the oven or heating compartments and facing the cooking plates enables a side closure to be provided which may be readily removed or swung down or aside in the space above the cooking plates so that at any 30 time access may be readily had to the entire distributing box, and consequently to all the various fuses, terminals and fittings installed thereon.

It will thus be seen that the distributing 35 box may be made up with the switches, fuses, terminals and all the wiring leading therefrom and installed as a single unit. This greatly facilitates and consequently reduces the cost of manufacture of the range. The 40 construction also enables any repairs or replacements readily to be made after the distributing box is in position. Furthermore, if any extensive repairs or replacements are required the distributing box may be readily 45 disconnected and removed from the range.

In the construction illustrated as a preferred form of the invention the distributing box is made of a single metal plate bent to have the form shown in transverse section in 50 Fig. 4. It comprises essentially a side wall 12 and a front wall 13. The upper, lower and rear ends of the box may be and preferably are entirely open. When in position the ends may be closed subject to requirements 55 of ventilation by adjacent portions of the range. As shown the rear end and the bottom end are left open while a warming oven 14 located on top of the broiler 11 extends over and covers the upper end of the 60 distributing box. The precise construction of the upper, lower and rear ends of the distributing box is, however, not essential. It is essential however that it present the side wall 12, the front wall 13 and the removable 65 closure at the opposite side wall.

This removable closure in the form illustrated is shown as a door 16 hinged at the bottom so that it may swing down over the cooking plates 7 exposing the entire interior of the distributing box. This closure 16 is 70 conveniently hinged to a plate 17 upstanding from the table 6 and it fits in beneath a plate 18 extending down from the bottom of the warming oven. A flange 19 is also shown integral with the front wall 13 of the distributing box extending rearwardly to the closure 16. But these are all details of construction which may be varied as desired. The main feature is to provide a closure 16 which may be removed or swung aside from 80 the distributing box over the cooking plates.

The switches controlling the heating units are mounted on the front wall 13 of the distributing box. As illustrated the switches 20, 21, 22 and 23 control respectively the 85 four cooking plates 7, the switches 24 and 25 control the lower and upper heating units respectively of the oven 10, and the switch 26 controls the heating unit of the broiler 11. Other connections may be installed on the 90 front wall 13 of the distributing box as desired and as illustrating this feature a receptacle 27 is shown to which connection may be made with a flat iron, percolator, toaster or other device.

The distributing box when in place rests upon the table 6 against the side wall of the oven or tier of heating compartments and is fastened securely but removably in place as by suitable screws 28.

100 The various electrical fittings on the distributing box will be varied according to the particular requirements. Preferably as already pointed out the main circuit wires 29 and 30 enter through the back of the range 105 and through the open rear end of the distributing box and preferably also the main line switch 31 is mounted on the side wall 12 of the distributing box. This enables the range to be installed simply by connecting 110 the main circuit to the terminals 32, 33.

Fuses as required are mounted on the side wall 12 of the distributing box. As illustrating this feature are shown the fuses 34 for the main line and the fuses 35 arranged 115 in a vertical row for each heating unit.

The wires extending to the oven or vertically arranged heating compartments lead directly through the side wall 12 of the distributing box and through the adjacent side 120 walls of the oven. In the case of the lower heating unit of the oven 10 an insulator 36 with three openings is provided and through these openings the wires 37, 38 and 39 extend to the heating unit inside the oven. A 125 bracket 40 is mounted on the side wall 12 of the distributing box and extends out adjacent the insulator 36. On this bracket are mounted binding posts 41, 42 and 43 to which the wires 39, 38 and 37 respectively 130

lead, and from which the circuit wires lead to the corresponding switch 24. The construction is the same with respect to each oven or vertical heating compartment heating unit. Hence when it is desired to remove the oven heating unit all that is necessary is to disconnect the wires 37, 38 and 39 from the terminals, and then they may be withdrawn through the insulator 36 into the ovens. The arrangement for distributing the circuit wires are similar in the case of the upper heating unit of the baking oven, similar connections being made to the bracket 44 as to the bracket 40. The same arrangement is also provided for any additional vertically arranged heating compartments as indicated in the connections made to the bracket 45 which connections extend to the broiler 11 shown in a compartment 20 above the baking oven.

It will be understood that the fuses, terminals and other fittings may be arranged as required upon the side wall 12 of the distributing box and that various other fittings 25 as required may be arranged upon this side wall. This construction enables all the electric fittings required to be mounted upon the distributing box and the connections to be made to the switches, receptacles or other 30 devices on the front wall of the distributing box so that the entire electric mechanism excepting the direct connections with the heating units may be assembled and mounted upon the distributing box before it is placed 35 in position in the range and so that after the distributing box is in position in the range ready access may be had through the side of the distributing box to all of these devices and at a position, namely over the cooking 40 plates, where this access enables these devices to be repaired, replaced, connected and disconnected or changed or added to as required.

Having fully described my invention what 45 I claim as new and desire to secure by Letters Patent is:

1. An electric range comprising a horizontal table provided with cooking plates, an oven extending vertically with respect to 50 said table, a distributing box mounted against the side wall of the oven adjacent the cooking plates, switches for the various heating units of the range mounted on the front face plate of said distributing box, and 55 a side closure for the distributing box opening toward said cooking plates whereby ready access may be had to the various electric fittings in said distributing box.

2. An electric range comprising a horizontal table provided with cooking plates, an oven extending vertically with respect to 60 said table, a distributing box mounted against the side wall of the oven adjacent the cooking plate, switches for the various heating units of the range mounted on the front 65

face plate of said distributing box, fuses, terminals and other electric fittings mounted on the side wall of said distributing box with circuit connections extending directly through the said side wall to the oven and 70 through the ends of the distributing box to the cooking plates and the main circuit, and a side closure for the distributing box opening toward said cooking plates whereby ready access may be had to the various electric fittings in said distributing box. 75

3. An electric range comprising the construction defined in claim 1 in which the side closure is a door plate covering substantially the entire side of the distributing box and 80 pivotally mounted to swing over the cooking plates.

4. An electric range comprising the construction defined in claim 2 in which the side closure is a door plate covering substantially 85 the entire side of the distributing box and pivotally mounted to swing over the cooking plates.

5. An electric range comprising the construction defined in claim 1 in which the 90 said distributing box is removably secured to the range so that the electric fittings may be assembled thereon before it is placed in position.

6. A distributing box for an electric range 95 comprising a side wall to which are secured the various fuses, terminals and other electrical fittings for distributing current from the main line circuit to various heating units of the range, a front wall on which the various switches for controlling the heating units are mounted, and a removable opposite side wall to enable free access to be had to said fittings.

7. A distributing box for an electric range 100 having the construction defined in claim 6 in which openings are provided in the fixed side wall to permit circuit connections to be made directly with heating units of an adjacent oven. 110

8. A distributing box having the construction defined in claim 6 in which one of the fittings mounted on said side wall is a switch having connections with and controlling the main line circuit. 115

9. A distributing box having the construction defined in claim 6 in which the rear end and at least one of the upper or bottom ends of the box is open to permit direct connections to be made with the main line circuit 120 and with heating units of the range.

10. An electric range comprising an oven with a heating unit located therein, a distributing box removably mounted against the side wall of the oven, an aperture in the 125 side wall of the distributing box and oven permitting the circuit wires to extend directly through the side wall of the oven to the heating unit, electric terminals mounted on the side wall of the distributing box ad- 130

adjacent said aperture, a switch mounted on the front plate of the said distributing box and electrical connections from the main circuit to said terminals and from said terminals to said switch.

11. An electric range having the construction defined in claim 10 in which a

bracket is secured to the side wall of the distributing box adjacent said aperture and in which the said terminals are carried by the 10 said bracket.

In testimony whereof, I have signed my name to this specification.

FRANK W. HEWITT.
